UNITED STATES PATENT OFFICE.

THOMAS NATHAN RUSSELL, OF CHICAGO, ILLINOIS, ASSIGNOR TO CHICAGO-CLEVELAND
CAR ROOFING COMPANY, A CORPORATION OF ILLINOIS.

CAR-ROOF.

1,265,523.

Specification of Letters Patent. Patented May 7, 1918.

Application filed September 1, 1914. Serial No. 859,675.

To all whom it may concern:

Be it known that I, THOMAS NATHAN RUSSELL, a citizen of the United States, residing at Chicago, in the county of Cook and 5 State of Illinois, have invented a new and useful Improvement in Car-Roofs, of which the following is a specification.

The invention relates to outside metal roofs for freight cars, and has in view several features of improvement which are partly improvements in the roof patented to me December 2, 1913, No. 1,080,173. The present improvements are concerned with the formation of the seam by which the 10 edges of the roof sheet, along the lines from the ridge to the eaves are united with each other, in such manner as to make such seam a perfect water seal, and also to make it strongly resistant to any superimposed 15 weight, and at the same time to save metal in the roof sheet and in the seam. This result is attained by an improved conformation of the interlocking edges of the roof sheets, so that the above advantageous results are attained without necessitating the use of a separate, external seam cap. With, 20 and as a confining and supporting means for, the said seam I employ an eaves seam clip of improved construction, arranged to 25 confine the seam upon the top, and at the sides, and also supported from below, at the same time providing for the ready escape of cinders, dust and moisture.

With such objects in view the invention 30 consists in the parts and combination thereof hereinafter set forth and claimed.

In order to make the invention more clearly understood there are shown in the accompanying drawings means for carrying 35 the same into practical effect, without limiting the improvements, in their useful applications, to the particular construction which, for the purpose of example, has been delineated. In said drawings—

Figure 1 is a plan view, partly broken away, of a car roof embodying the invention.

Fig. 2 is a vertical transverse section of the roof, on line II—II of Fig. 1, a portion of the same being broken away.

Fig. 3 is a similar section of the eaves

portion of the roof, on a larger scale, on line III—III of Fig. 6.

Fig. 4 is a transverse vertical section showing the ridge seam by which the roof 55 plates are united.

Fig. 5 is a vertical section, on line V—V of Fig. 1, and partly broken away, showing portions of two of the roof sheets united to 60 form a seam.

Fig. 6 is a side view of a portion of the roof, and car, the running board saddles being shown in section.

Fig. 7 is a perspective view of one of 65 the roof sheets.

Fig. 8 is a perspective view, partly broken away, of a flashing which may be employed to underlie the eaves edge of the roof sheet and to extend down over the upper part 70 of the fascia.

Fig. 9 is a perspective view of the same 75 clip.

Referring to the drawings, 1 indicates the ridge pole of the car, 2 the side plates, 3 the carlines, here shown as consisting of angle irons extending from side to side of the car and bent to conform to the slopes of the roof, and sustaining on their horizontal flanges filler bars 4 in the nature of rafters, on which latter is sustained the top 80 sheathing 5. The carlines, ridge pole and running board saddles 6 are united by vertical through bolts 7. The vertical flange of the carline is bent longitudinally of the car as shown at 8, and is secured to the 85 inner face of the side plate by a bolt 9. The horizontal flange of the carline is bent upward along the inner face of the side plate, outward along the top of the same, where it may fit in a suitable recess, and 90 downward against the outer face of the side plate, as shown at 10, where it is secured by a bolt 11. The side sheathing is shown at 12, attached at its upper part to the outer face of the side plate, and recessed where 95 necessary to receive the said flanges 10 of the carlines. The upper end of the upper part of the side sheathing is overlaid by the side fascia 13, which is secured in place by the bolts and nails of the eaves seam 100 clips. The eaves clips are shown at 14 and may be of any form suitable for the purpose,

to confine the bent down eaves edges of the roof sheets.

15 indicates the roof sheets, each of which is formed at its ridge end so as to unite in 5 a ridge seam with a contiguous roof sheet at the other side of the ridge. A seam suitable for this purpose is shown in Fig. 4, where one of the sheets is shown as formed with an outer inverted U-flange 16 bent 10 away or outward from the main body of its sheet, and the corresponding sheet at the other side of the ridge is formed with an inner inverted U-flange 17 bent toward and overhanging the main body of the sheet 15 by a return bend. The parts of this seam can be united by mere superposition, and do not interlock so as to require to be slid or telescoped together by movement longitudinally of the seam. This form of ridge 20 seam can therefore be combined with side seams, extending from the ridge to the eaves, which completely interlock and require to be telescoped together. There is a tendency in the ordinary form of ridge 25 seam, in which a U-bend, which is bent away or outward from the top of the sheet, is superposed over a similar U-bend, for the seam to be caused to open more or less and gape by reason of the tendency of the sheets 30 to work down the inclined planes away from the ridge. When the usual form of seam gapes in this manner a dashing rain will work through the seam in places and cause leakage in the car. This difficulty is not 35 experienced with the form of ridge seam which I employ and have illustrated, the action of which is to catch rain which enters under the return bend 17 and return it upon the top of the roof sheet instead of conducting it farther into and between the parts 40 of the seam, and such seam can also be employed, as above explained, in combination with said seams which interlock and the parts of which must be telescoped together. This structure also forms a very 45 strong, as well as water excluding, ridge seam independent of any extended ridge cap. I however employ at the points where four sheets meet, short four armed ridge 50 caps 18, which are confined by the running board saddles and have perforations for the through bolts 7. By reason of the said formation of the flanges 16 and 17 the roof sheets at one side of the car are not all exact 55 duplicates of the sheets at the other side of the ridge. But my improved side seam can be used with the ordinary form of ridge seam. At the eaves end the roof sheet is formed with an extended flange 19 bent 60 downwardly over the fascia, and confined by the eaves clips 14. Each of the roof sheets is formed along one of its transverse edges (which extends transversely of the car from the eaves to the ridge) with a 65 double flange 20, 21, and along its other

transverse edge with a triple flange 22, 23, 24. The members 20 and 21 of the double flange are or may be parallel with one another and are united at the top by a bend 25, and this flange is turned inwardly toward the body of the sheet so that the member 21 overhangs the same. The members 22 and 23 of the triple flange, together with a connecting arched portion 26, form a segment of a tube, such segment being 70 considerably more than a half circle. The third flange member 24 extends upward within the tube. The said parts are so proportioned that the double flange of one sheet may interlock with the triple flange 75 of the next sheet, as best seen at the middle of Fig. 5, so that the flange member 24 is included within the flange members 20 and 21, and the latter are included within the said triple flange, the latter taking the place 80 of and forming in effect a seam cap which is capable of being supported from below by a suitable eaves seam clip. Each roof sheet so formed is or may be the counterpart of every other and yet comprises a strong, leak-proof and efficient seam cap. 85

The eaves seam clips are shown at 27, each of the same being formed at its middle part with a hood 28 which is nearly tubular, so as to fit around and partly beneath the 90 outer ends of the said caps or triple flanges 22, 23, 26. From this hood are extended inwardly a top projection 29 which holds the cap down by an extended bearing, and two bottom projections 30 which fit at the 95 sides of and partly under the flange members 22 and 23. The cap portions of the roof sheets are thus closely confined in place and supported from below, while the opposite edge of the roof sheet formed with the 100 double flange 20, 21 is left free and movable as may be necessary relative to all other parts, under the torsional movements of the roof. From the hood 28 the seam clip is 105 curved outwardly and downwardly to conform to the flange 19, two contiguous ends of which flanges it confines (Fig. 6), and its lower part branched into arms 31 which are perforated so that they may be secured by nails to the fascia and side sheathing. The downwardly extended part of the seam 110 clip is perforated to receive a bolt 32 which passes through to the inner side of the side plate. 115

What I claim is:

1. In a car roof, the combination of roof sheets having interior and exterior interlocking seam flanges formed on their side edges, the said flanges being spaced from each other to allow play of the interior 120 flanges relative to the exterior flanges, and means securing each sheet at one eaves-corner by gripping the eaves end of the exterior seam-flange, the other eaves-corner being free to move within its seam, whereby 125 130

each sheet is held positioned along one eaves-to-ridge seam-line only and is free of the shifting of the substructure of the roof under the body and other side seam flange 5 of such sheet.

2. In a car roof, the combination of roof sheets having interior and exterior interlocking seam flanges formed on their side edges, the said flanges being spaced from 10 each other to allow play of the interior flanges relative to the exterior flanges, and seam clips fixed on the eaves of the car and holding the exterior flanges in position along the normal seam line, the other or 15 interior flanges of the sheets being left free.

3. In a car roof, the combination of roof sheets having interior and exterior interlocking seam flanges formed on their side edges, the said flanges being spaced from 20 each other to allow play of the interior flanges relative to the exterior flanges, the exterior flanges being of tubular form, and seam clips fixed on the eaves of the car and engaging below and supporting the exterior 25 flanges and holding them in position along the normal seam line, the other or interior flanges of the sheets being left free.

4. In a car roof, the combination of roof sheets having interior and exterior interlocking seam flanges formed on their side edges, the said flanges being spaced from 30 each other to allow play of the interior flanges relative to the exterior flanges, and seam clips fixed on the eaves of the car and engaging partly under and at the sides and 35 on top of the exterior flanges and holding the exterior flanges in position along the normal seam line, the other or interior flanges of the sheets being left free.

5. In a car roof, the combination of roof sheets formed with and directly united by exterior and interior interlocking side seam flanges, and seam clips supported on the 40 eaves of the car and supporting exteriorly from below the said flanges.

6. In a car roof, the combination of roof sheets formed with and united by exterior and interior interlocking side seam flanges,

and seam clips supported on the eaves of the car and engaging under and supporting 50 exteriorly from below the exterior ones of said flanges.

7. In a car roof, the combination of roof sheets formed with and united by exterior and interior interlocking side seam flanges, 55 the said exterior flanges being tubular and spaced from the interior flanges, and seam clips supported on the eaves of the car and engaging under and supporting exteriorly from below the exterior ones of said flanges. 60

8. In a car roof, the combination of roof sheets united at their sides by loosely interlocking side flanges, and confined at their eaves ends, and united by bent flanges to form a ridge seam, the sheet at one side of 65 the ridge having an outward U-bend away from the body of the sheet and the sheet at the other side of the ridge having a return bend over the body of the sheet and contained within the said outward U-bend. 70

9. In a freight car roof, the combination of roof sheets united by bent flanges to form a ridge seam, the sheet at one side of the ridge having an outward U-bend and the sheet at the other side of the ridge having 75 a return U-bend contained within the outward U-bend, said U-bends being open and downwardly and outwardly flaring for the direct superposition of one sheet on the other. 80

10. In a freight car roof, the combination of roof sheets united by side seams consisting of interlocking side flanges requiring to be telescoped together, and united at the ridge by U-bends adapted to be superposed 85 one on another, the sheet at one side of the ridge having an outward U-bend and the sheet at the other side of the ridge having a return U-bend contained within the outward U-bend. 90

In testimony whereof I affix my signature in presence of two witnesses.

THOMAS NATHAN RUSSELL.
